UNITED STATES PATENT OFFICE.

ANTOINE ISIDORE ODIER, OF PUTEAUX, FRANCE.

STARTING APPARATUS FOR USE WITH INTERNAL-COMBUSTION ENGINES AND OTHER PURPOSES.

1,351,399.

Specification of Letters Patent. Patented Aug. 31, 1920.

Application filed July 16, 1918. Serial No. 245,214.

To all whom it may concern:

Be it known that I, ANTOINE ISIDORE ODIER, a citizen of the French Republic, residing at No. 64 Quai National, Puteaux, France, have invented certain new and useful Improvements in Starting Apparatus for Use with Internal-Combustion Engines and other Purposes, of which the following is a specification.

10 This invention has for its object to provide an improved apparatus by means of which rotary motion may be imparted to a shaft and more particularly to the shaft of an internal combustion engine for the purpose of 15 starting the said engine.

The improved apparatus comprises essentially a cylinder wherein pressure is produced which is used to push a piston. This piston carries a pulley on which a rope is 20 wound that is attached at one end to a fixed point, and at its other end to an opposing spring after a certain number of turns of the rope have been wound on a pulley which is connected to the shaft to be started.

25 The manner in which this invention is to be performed will now be more particularly described with reference to the accompanying drawings which illustrate by way of example two constructional forms of the 30 improved apparatus of this invention.

In these drawings:

Figures 1 and 2 are respectively a side elevation and a plan of a first form of the improved apparatus, and

35 Fig. 3 is a vertical cross section on the line I—I of Fig. 2.

Fig. 3^a is a diagrammatic front view of the pulley and rocking beam shown in Fig. 3.

40 Figs. 4, 5 and 6 are similar views of a second form of the improved apparatus; Fig. 6 being a vertical cross section on the line II—II of Fig. 5.

Referring first to Figs. 1 to 3, a shaft 1 is fixed to the engine shaft, and upon this 45 shaft 1 there is riveted or otherwise suitably fixed a rocking beam 2 carrying at each end pawls 3 which are adapted to engage in suitable recesses formed in the rim of a pulley 4 that is loose on the shaft 1. These pawls are 50 arranged in such a manner that they are driven when the pulley 4 is rotated in the direction of rotation of the engine to be started, whereas they slip idly when the pulley 4 is rotated in the reverse direction.

55 These pawls are acted upon by springs that

have a tendency to keep the pawls in engagement and they are so counter-balanced that when a determined speed is exceeded, the action of the springs is neutralized by centrifugal force and the pawls are released, 60 whereupon the latter continue to revolve out of frictional contact with the pulley.

The foregoing mechanism has been described here owing to its suitability for use with the improved apparatus, but it is 65 merely an application of a well-known expedient.

A casing 5 incloses the entire mechanism and constitutes at one point the bolted support for a cylinder 7 the emplacement for 70 which is indicated at 6 (Fig. 3).

The cylinder 7 (Figs. 1 and 2) consists of a tube, preferably of steel, and incloses another tube 8 that is arranged to slide with a certain amount of "play" in the cylinder 7. 75 The tube 8 terminates at one end in a tight-working piston (not shown), and at its other end in a bracket 9 in which is journaled a grooved pulley 10 arranged in the axis of the cylinder. A flexible rope 11 passing over 80 this pulley is attached at one end to a fixed point 12 of the apparatus (Fig. 2). The other end of the rope 11 passes inside the casing 5 to the pulley 4 on which it is wound.

The fixed point 12, the pulley 10 and the 85 pulley 4 are so arranged as to cause the two stretches of the rope 11 to run parallel with the axis of the cylinder 7. The result of this arrangement is that any strain exerted upon the rope by the piston will be distributed 90 equally to the two stretches, and therefore the piston, not having to sustain any racking strain will not require exact guidance and it will have to overcome no other friction than that due to its packing and the friction of 95 the pulley on its axle.

Moreover, for a given length of stroke of the piston, the rope will travel through a distance equal to double the said length, so that the bulk of the apparatus is reduced by 100 half for a determined starting movement.

The foregoing arrangement constitutes a new application of a well known type of pulley tackle.

After the rope 11 has been wound a few 105 turns around the pulley 4, the rope passes to the outside of the casing 5 where it is led over a pulley 14 and is attached to an opposing spring or tensioning device 13.

In the example shown the tensioning de- 110

vice 13 consists of a rubber rope of the kind used in what are known as Sandow exercisers, which passes around a pulley 14' and is attached at its other end to a suitable bracket.

The pulleys 14 and 14' are provided for the purpose of reducing the bulk of the apparatus.

In either case however the entire arrangement should be such that the point of attachment 15 of the rope 11 to the tensioning device 13 shall not be able to pass a stop 16 which may be constituted by leaving only a too narrow space between one of the guide pulleys and the cylinder. The rope must however be long enough to remain unstrained when the piston is at the end of its stroke and the tensioning device is bearing against the stop.

On the piston being started or moved, the pulley and consequently the engine to be started, will be moved only after the piston has traveled through the distance necessary for tensioning the rope and after the tensioning device 13 has been moved away from its stop so that the said device has caused a certain amount of resistance to the movement of the rope. By this means the starting will take place gradually, which is important when an explosively acting medium is employed for propelling the piston of the apparatus. This is one of the characteristic features of the invention, whereby a gradual starting is produced by a novel application of a known means.

It may also happen that the engine when started, instead of continuing its rotation in the normal direction, is thrown back violently in the reverse direction, for instance, by the action of a premature ignition. In such a case the piston of the apparatus is moved back to the end of its stroke by the engine but as at that instant the stop 16 acts to limit the returning movement of the tensioning device 13, the stretch 17 of the rope 11 will not be strained and therefore no friction will be produced. Consequently the pulley 4 is not held by the rope and it can revolve freely in either direction. The starting apparatus is therefore not subjected to any strain beyond that for which it has been designed. By this novel application of the well known law of friction, the strength of the parts and more particularly of the attachment of the casing 5 to the engine need be calculated only for the starting strain, instead of for the much higher strain caused by the sudden reversing of the engine.

Fig. 3 indicates the provision of hand gear 18 for actuating the starting apparatus for use when the available pressure in the generators is exhausted.

Figs. 4, 5 and 6 illustrate a constructional form of the improved apparatus wherein

the provision of pawls that are moved into and out of engagement by springs and centrifugal action respectively, is dispensed with. In other respects the general arrangement of the apparatus is the same as in the constructional form first herein described. 19 is a pipe for conveying pressure fluid from any suitable supply 19' to a plunger 20 which works in a small cylinder 20' and is pushed by the fluid (from the right toward the left hand of Fig. 6), compressing a spring 21, and in this movement pushes a square shaft 22. This shaft has on its end a claw clutch member 23 which is thereby caused to engage the complementary claw clutch member 24 fixed on the engine shaft to be started.

When the plunger 20 has been moved back sufficiently to cause the engagement of the clutch 23, 24, it will then uncover an orifice 25 through which the pressure medium issues and passes through the pipe 26 into the cylinder, and acts upon the piston therein so as to produce the same operations as those described with reference to Figs. 1, 2 and 3.

The actuation of the piston in the said cylinder may be effected by the expansion of any suitable pressure medium, for instance, gas, but it is preferred to use either compressed air because it is an easier matter to change the compressed air generators, or to use liquid carbonic acid because the vessels containing the latter have a very small weight and bulk. Another convenient method is to utilize the "deflagration" of a suitable gas because it is easy to prepare beforehand cartridges of small size for the purpose in view.

What I claim is:—

1. A starting apparatus comprising in combination a cylinder, a piston member in the cylinder arranged to be worked by pressure fluid, a pulley mounted on the piston member, another pulley mounted for turning the engine shaft, a spring attached to a fixed part and a rope attached at one end to a fixed part adjacent the cylinder and at the other end to the spring and adapted to pass over the pulley mounted on the piston member and around the other pulley for turning the engine shaft.

2. A starting apparatus as claimed in claim 1 and comprising a third pulley, a bracket carrying this pulley and fixed to the end of the cylinder away from the piston, a fourth pulley, a second bracket carrying the fourth pulley and mounted upon the cylinder adjacent the other end and a tension device passing around the fourth pulley and wherein the rope passes over the third pulley and is attached to the tension device, the other end of the tension device being secured adjacent the third pulley.

3. A starting apparatus as claimed in

claim 1, wherein a stop is provided limiting the return movement of the spring, the arrangement being such that the pulley for turning the engine and consequently the engine will be moved only after the piston has traveled through the distance necessary for tensioning the rope after the spring has moved away from its stop so that the said spring has caused a certain amount of resistance to the movement of the rope, whereby the starting effect will take place gradually.

4. A starting apparatus as claimed in claim 1, and comprising clutch members between the pulley for starting the engine and the engine shaft, a spring adapted to keep the clutch member out of engagement and means for causing the clutch member to engage as and when required consisting of a

small cylinder having two orifices, a plunger 20 working in the small cylinder, a conduit coupled with the source of supply of working fluid and adapted to connect with one of the orifices in the small cylinder, and another conduit communicating with the other 25 of said orifices and with the cylinder in which the piston of the apparatus works, the arrangement being such that on fluid being admitted to the small cylinder the plunger causes the engagement of the clutch members 30 while at the same time the plunger in its movement uncovers the orifice leading to the cylinder of the apparatus and supplies thereto the fluid for working the piston.

In testimony whereof I have signed my 35 name to this specification.

ANTOINE ISIDORE ODIER.
